UNITED STATES PATENT OFFICE

JAY WILL LYSONS, OF NEW YORK, N. Y.

IMPRINTING DEVICE

Application filed September 11, 1928. Serial No. 305,156.

My invention relates to certain types of printing devices permitting the reproduction of individual prints selected out of a chain or band of type plates commonly used in connection with addressing or similar devices.

One object of my invention is to provide a specially designed print duplicating device wherewith any desired member in a chain of suitable type plates may be inserted and printed without the necessity of detaching or otherwise disturbing the chain.

Another object is to produce a simple, efficient and inexpensive print duplicating device, positive in its operation and designed to permit its manufacture at the lowest cost of production.

The customary method employed to obtain an individual print out of a chain of type plates is to entirely detach the plate from the chain and re-insert the same again after printing.

It is a well known fact that it very frequently occurs to have an individual print of one or the other type plate reproduced thus causing not only a considerable loss of time but also tends to confuse the system of arrangement in the chain.

These and other objections I overcome by my novel printing device composed of various parts and elements fully described in this specification and illustrated in the accompanying drawings in which:

Figure 1 represents a partly sectional front elevation of such a printing device, embodying the features of my invention.

Figure 2 represents a partly sectional plan view of the printing portion of the device, along lines 2-2 in Figure 1.

Figure 3 represents a plan view of complete device.

Figure 4 represents a partly sectional side view of Figure 3, along lines 4-4.

Figure 5 represents a detailed view of a chain of type plates, as commonly used in connection with addressing and similar duplicating devices.

Figure 6 represents a side view of the chain of type plates shown in Figure 5.

Similar numerals refer to similar parts throughout the drawings.

Upon a common base plate *a*, shown in Figures 1 and 4, the stationary supporting member *b* is rigidly mounted and held in position by a pair of suitable studs *c* and *c1*. Member *b* is provided with a bearing *b1* serving as a pivot for the operating lever *d*, which in turn is movably interconnected with a plunger *e*, by means of a slot *d1* and pin *e1*. Plunger *e* being slidably guided in supporting member *b*, is normally held in its upward position by *a*, preferably conically wound, coil spring *f* pressing against collar *e2* which forms a part of plunger *e*. The lower part of plunger *e* is shaped into an elongated rectangular head *e3* whose function is to perform the printing operation described further below. A cage comprising the two lower prongs *i* and the two upper prongs *i1*, rigidly held together, is securely mounted upon the rectangular plunger head *e3*. This cage serves the purpose of engaging and holding the type plates *l* in position. A platform *g*, the central portion of which is suitably cut out, is also rigidly mounted upon plunger head *e3*. Screws *h* serve the purpose of securely mounting cage members *i*, *i1* and platform *g* upon head *e3*. (See also Fig. 4.)

The type plates, as shown in Figures 5 and 6, are suitably linked together and present a chain, which in turn may be wound and unwound upon suitable spools, not indicated in the drawings.

A centrally positioned padded stem *h* is removably held in position by suitable supports *m* and *m1*, also mounted upon base *a*.

The inking ribbon *n* may be conveniently wound or unwound upon removably arranged spools *o* and *o1*, supported in brackets *o2* and *o3*. The ribbon *n*, spools *o* and bracket *o2* are of conventional design and do not form a part of this invention and for this reason need not be described in detail.

The device is functioning as follows: After selecting the type plate of which a duplicate print is to be made and without detaching the same from the chain it is inserted into the cage, that is between the lower prongs *i* and the upper prongs *i1*, as clearly indicated in Figure 1.

An envelope or any other suitable medium

upon which a print is to be reproduced is then inserted into the gap formed between platform *g* and the padded stem *h*. With these members now in position the plunger 5 *e* is forced downward by means of the manually operated lever *d*, whereby plunger head *e3* and cage *i* and *ii* are forced against the envelope or other medium. Now by means of the interposed inking ribbon a clear 10 print is produced upon the medium. This printing operation, of course, can be repeated as often as desired or another type plate inserted as described above.

Having thus fully described my invention 15 I do not wish to limit myself to the exact details of construction as disclosed in this form of embodiment, it being apparent that there may be considerable variations in the design of this device without departing from the 20 spirit of my invention.

What I claim as new and desire to secure 80 by Letters Patent is:

1. In a device of the character described, a 85 movable printing member, manual operating 25 means for said printing member, suitable type plate engaging and holding means forming a part of said printing member, a suitably arranged platform also forming a part of said movable printing member to serve the 30 purpose of supporting and guiding an inking band and to actuate in unison with said printing member substantially as and for the purpose set forth.

2. In a device of the character described, a 90 35 movable printing member, and manual operating means for said movable printing member, said printing member comprising a suitably shaped plunger whose lower or operating portion is provided with a suitable type 40 plate engaging and holding means and a suitable platform also to form a part of said plunger for the purpose of supporting and guiding an inking band and to actuate in unison with said printing member, substantially 45 as and for the purpose described.

3. In a print duplicating device of the 95 character described, a movable printing member, manually actuated operating means for said movable printing member, and said movable printing member comprising a suitably shaped stem whose lower or operating end 50 is shaped into a suitable head upon which a plurality of suitable type plate engaging and holding members and a suitable inking 55 ribbon-platform are mounted and operated in unison with said stem, substantially as and for the purpose set forth.

4. In a print duplicating device of the 100 character described, a slidably arranged printing 60 plunger, the lower or operating portion of said sliding plunger forming a suitable head, supporting and holding a plurality of type plate engaging prongs and a suitable platform for the purpose of supporting and guiding 65 a suitable inking band and said type plate

engaging prongs and said inking band supporting platform disposed to operate in unison with said manually operated sliding plunger, substantially as and for the purpose set forth.

Signed at the city of New York in the county of New York and State of New York June, A. D. 1928.

J. WILL LYSONS.
